UNITED STATES PATENT OFFICE.

EMILIO MAGALDI, OF NAPLES, ITALY.

SHOE.

Application filed May 14, 1920. Serial No. 381,486.

To all whom it may concern:

Be it known that I, EMILIO MAGALDI, a subject of the King of Italy, and resident of Naples, Italy, have invented certain new and useful Improvements in Shoes, of which the following is a specification.

The present invention relates to the manufacture of shoes, and more particularly to that part of the shoe which is the sole.

10 The purpose of the invention is to attain a good ventilation of the lower part of the shoe, to condense the vapors given off by the foot, to preserve the parts constituting the bottom of the shoe and to make its outside 15 and inside impermeable.

The invention is illustrated in the accompanying drawings in which:

Figure 1 is a top view of the sole according to the present invention.

20 Figure 2 is a bottom view of the same sole.

Figure 3 is a plan view of the semirigid sole.

Figure 4 is a section on the line 4—4 of Figure 3;

25 Figure 5 is the outside sole of the shoe;

Figure 6 is a section on the line 6—6 of Figure 5;

Figure 7 shows a pad or insole;

Figure 8 is a section of Figure 7 on the line 30 8—8, the filling of the pad being omitted;

Figure 9 shows the attaching means for the sole and for the heel;

Figure 10 is a longitudinal section of the complete sole;

35 Figure 11 is a section on line 11—11 of Figure 10.

Referring to the drawing the sole A is composed of one or more layers of fabric B preferably impermeable linen applied on a 40 semirigid core C, made of resilient wood, the fabric being rounded about and along the edges of the fore part of the sole to form chambers D. In each chamber is arranged a coiled spring E, and its purpose is to constitute a passage for the circulation of the air necessary for the peripheric ventilation of the shoe. The core C is covered by one or more layers of fabric B and secured by means of the stitches F which serves also 45 to seam the leather of the shoe to the sole.

50 H indicates a flat spring secured to the sole at 1, 2, 3 and 4 by means of the U-shaped members I and L shown in Figure 9, the ends of which are threaded to receive nuts.

The free end of the spring H passes under 55 the joining part or bridge of the member M, which with member N serve to secure the heel to the shoe.

The purpose of the spring H is to preserve the shape and elasticity of the sole. 60 The screws furthermore serve to attach to the shoe the protecting devices for instance rubber pads or the like.

The outer sole shown in Figure 5 is composed of layers of impermeable fabric provided with a strip of leather sewed to the 65 layers and to the shoe.

The pad O is preferably made of wool or the like material enclosed within an envelope of fabric. The shape and profile of the pad 70 is such that it does not entirely fill the space between springs E, but leaves a certain space necessary for the free movement of the toes. The movements of the foot causes springs E to be compressed so that the springs in returning to their original shape produce a 75 circulation of air and thereby ventilate the shoe.

Having now particularly described and ascertained the nature of my invention and 80 in what manner the same is to be performed what I claim is:

1. A shoe having a sole formed of a pad O of soft material enclosed in a covering of fabric, a semirigid sole C, having on its 85 edges a coiled spring, and an insole A, composed of several layers of impermeable fabric on which layers a flat spring is screwed to keep the shape of the shoe, the insole as well as the semirigid sole and the coiled 90 springs being enveloped in a covering composed of several layers of fabric and forming a peripheric chamber for the ventilation of the shoe whose outsole is formed of several layers of impermeable fabric. 95

2. A shoe having a sole formed of a wooden member, coiled springs at the forward part of the side edges, a flat spring secured to the instep portion of the sole, and a covering of fabric enclosing the sole and 100 springs.

In testimony whereof I have hereunto signed my name in the presence of two witnesses.

EMILIO MAGALDI.

Witnesses:

W. B. NUSBAUM,
DINLIO NARDONI.
